RADIO RECEIVER

Kikuo Ohta, Neyagawa-shi, Osaka, Japan, assignor to
Matsushita Electric Industrial Co., Ltd., Osaka, Japan,
a corporation of Japan

Filed Sept. 6, 1968, Ser. No. 13,409

Term of patent 14 years

Claims priority, application Japan Mar. 23, 1968

Int. Cl. D14—03

U.S. Cl. D56—4

FIG. 1

FIG. 2

FIG. 3

FIG. 4

FIG. 1 is a front elevational view of a radio receiver showing my new design;

FIG. 2 is a right side view thereof;

FIG. 3 is a top and front perspective view thereof showing opened dial board cover, and

FIG. 4 is a bottom and rear perspective view thereof.

The dominant features of my new design reside in the full line portion.

Portions of the figures are stippled to indicate contrast in appearance.

I claim:

The ornamental design for a radio receiver, as shown and described.
